KNITTING MACHINE

Leslie Herbert Leedham and Henry Harold Holmes, Leicester, England, assignors to Wildt and Company Limited, Leicester, England, a British company

Application August 6, 1936, Serial No. 94,666
In Great Britain August 12, 1935

10 Claims.

(Cl. 66—50)

This invention consists in improvements in or relating to knitting machines and has for its object to provide an improved patterning means therefore whereby a novel patterning effect can be obtained including a raised or plush pile design.

Hitherto in all plush pile design fabrics it has been customary to produce only a plain fabric upon which the plush pile design appears. By the present invention the plush pile design is enhanced by patterning of the unraised ground fabric.

The present invention has for its object to produce a pattern in the ground fabric that is unraised from the surface thereof and also in addition a raised or plush pile pattern and for this purpose comprises the combination of needle selecting patterning means and sinker selecting patterning means both including intermittently rotatable patterning elements and driving means common to both said patterning elements.

This combination may be provided in association with any desired one or more or with all of the yarn feeds in a multi-feed machine.

In order that the invention may be more clearly understood a preferred example will now be described with the aid of the accompanying drawings, in which—

Figure 1 is a section, in a plane containing the axis of a circular knitting machine, showing those parts of the mechanism necessary for the understanding of the present invention and is a section on the line 1—1 of Figure 2;

Figure 2 is a plan of the parts shown in the upper portion of Figure 1;

Figure 3 is a section on the line 3—3 of Figure 1;

Figure 4 is a section on the line 4—4 of Figure 1, the pattern drum having been omitted for the sake of clearness;

Figures 5, 6, and 7 are respectively sections on the lines 5—5, 6—6, and 7—7 of Figure 4;

Figure 8 is a diagram in plan showing the action of the sinkers in relation to one of the yarn feeders;

Figure 9 is an elevation looking from below in Figure 8, and

Figures 10 and 11 are respectively sections on the lines 10—10 and 11—11 of Figure 8.

Like reference numerals indicate like parts in all the figures of the drawings.

In the example illustrated, the two patterning elements are in the form of rotatable pattern drums 20 and 21 but these may be obviously replaced by any other form of rotating selector preferred. Both drums in the illustrated example

are of the type described in copending United States application Serial No. 47,681, now Patent No. 2,078,571, that is to say, each pattern drum has at its outer surface a number of tricks extending parallel with the axis of the drum and into these tricks bits such as 22 and 23 respectively can be inserted having outwardly projecting butts such as 24 and 25 respectively arranged in any one or more of a plurality of different heights. For each height of butt there is a selector cam. For the upper drum 20 the selector cams are in the form shown at 26 (Figure 2) and all these cams are rotatably mounted on a spindle 27 mounted in ring 72 to be described later. Between the cams 26 and the bits 22 are interposed a plurality of cam followers 29, one associated with each cam 26, and these followers are pivotally mounted on a pivot 30 carried by bracket 28. Noses at opposite ends of each of the cam followers 29 extend across the gap as shown in Figure 2 between the bits and the cams so that as the pattern drum is rotated the bits will press inwardly and selectively those cams for which a butt is provided on a bit at the height of the nose of the corresponding follower 29.

For the lower drum 21 selector cams 31 are provided pivotally mounted on pin 49, and these cams operate for needle selection, in the manner to be described, without the intermediary of cam followers.

The needle cylinder 32 has needles 33 disposed in its tricks and held therein in known manner by spring bands 34 so as to allow the needles to slide freely in the tricks. Beneath each needle is an intermediate jack 35 and a main or selector jack 36, the lower end of each of which, as at 37, will by its own natural resilience spring outwardly from the cylinder trick. For each jack 36 there is a presser element 38 and these elements have outwardly projecting butts 39 situated at any one or more of a plurality of heights corresponding to the heights of selector cams 31. Those butts 39 where they are present will, as the drum 21 revolves, selectively move corresponding cams 31 outwardly and these will engage with butts such as 24 to move the corresponding presser 38 inwardly thereby pressing the lower end 37 of jack 36 inwardly and out of the path of a needle-raising cam 40. It will be obvious and well understood by those skilled in the art that by the choice of butts such as 24 in the several bits 23 and also by choice of butts such as 39 on the presser elements 38 selection of needles can take place according to a predetermined pattern lay out, those needles whose jacks 36 do not have their lower

extremities 37 pressed inwardly being the needles that will remain operative.

Similarly by choosing the position of butts such as 24 of the upper patterning element and also the positions of butts 41 on sliders 42 the latter will be caused selectively to operate sinkers 43 arranged in known manner at positions alternating with the needle heads in the needle cylinder.

10 The sinkers are carried for sliding movement radially of the needle cylinder between a sinker bed plate 44 and a cover 45, but as these parts in themselves are well known they are more or less diagrammatically illustrated in the drawings.

15 The cylinder cam box is illustrated at 46 and comprises needle actuating cams indicated at 47 in Figure 1 and at 48 there is illustrated an element between which and jacks 36 there will be relative rotation about the axis of the cylinder, 20 this member 48 serving, as described in copending United States application Ser. No. 90,660, to prevent the upper ends of jacks 36 from being tilted outwardly from their tracks as their lower ends are pressed inwardly by the action of cams 25 31.

As applied to a rotating cylinder machine patterning means may be applied to any one or more of the yarn feeds at which it is desired that patterning shall occur, and each such patterning 30 means will preferably comprise a combined unit. That is to say, at the lower portion a unit will comprise a needle-selecting drum such as 21 and its associated selector elements, and at the upper portion of the unit a second drum, such as 20, 35 will be provided together with its associated sinker operating selector elements.

In order to actuate the pattern drums, that is to say in order to move them around their axes step by step, a vertically disposed spindle 50 is 40 mounted in upper and lower bearings 51 and 52 provided in the structure of the unit, the upper bearing 51 being afforded in a portion of a bracket 53 supported from a cam box carrier plate 54 and the lower bearing being supported 45 on a base plate 55 of the machine.

The bracket 53 serves also as the main support for the cam followers 29 and is held stationary with respect to the sinker ring. At the lower portion of the unit the selector cams are carried 50 by a block 56 bolted to a ring 57 that is also stationary with respect to the needle cylinder.

It is to be understood, however, that the design of the supporting structure for the patterning mechanism may be of any other preferred form 55 as of itself it does not constitute part of the present invention.

The spindle 50 is a rocking spindle and has secured to its lower end (see Figure 3) a radial arm 58 to which one end of a racking pawl 59 is 60 pivotally connected at 60. The other end or nose of the pawl 59 engages with the teeth provided on the drum 21, for example with teeth constituted by the lowermost butts 61 provided for this purpose on each of the bits 23. Similarly, 65 at its upper end as shown in Figure 2, the spindle 50 is provided with a radial arm 62 and a racking pawl 63 pivotally connected at 64 to the arm 62. The nose of the pawl 63 co-operates again with a ring of teeth afforded in the drum 20, this 70 ring of teeth preferably being constituted by lower butts 65 provided on each of the bits 22.

In addition there is secured to the lowermost extremity of spindle 50 the double arcuate rocker arm 66 (Figures 1 and 3) the two extremities of 75 which are engaged alternately with a racking

cam 67 that rotates in company with, or in synchronism with the needle cylinder. For example, it is secured to the lower cylinder support ring 68. As the racking cam passes the double rocker arm 66 it will first engage one extremity (the lowermost one in Figure 3) to move it outwardly and in so doing will provide a racking stroke for the pawl 63 of the sinker selecting drum, thus turning the latter through an angle equivalent to one tooth space. During the traverse of cam 67 past the rock arm 66 that extremity first engaged will be left free and the other extremity (the uppermost one in Figure 3) will then be contacted by cam 67 to turn spindle 50 in the opposite direction, thus providing a rocking stroke for drum 15 21, the latter being thereby rotated through an angular distance equivalent to one tooth space. These movements are clearly to be seen from a consideration of Figures 2 and 3, in which the direction of rotation of the cylinder, and also the 20 cam 67, is shown by the arrow on the left-hand sides of those figures. During the working stroke of one pawl the other one makes an idle stroke and slides over a tooth of the pattern drum with which it is associated under the pull of tension 25 springs 69, both springs normally tending to hold the pawls in engagement with their respective teeth.

The lay out of the racking cam 67 relatively to the ends of the rock arm 66 is such as to ensure that a change-over in pattern both for that produced by the needle and for that produced by the sinkers, will occur in the same or substantially the same vertical line down the length of the fabric. As it is necessary that needle selection shall occur at a position spaced angularly from that at which sinker selection must take place, the angular distance between the two ends of the rock arm will be chosen accordingly so that as the cylinder rotates both the pattern changes 40 35 occur approximately along the same vertical line or wale of the fabric.

For convenience, and as illustrated in the drawings, any one combined pattern unit serves to adjust the needles for one yarn feed, whereas 45 the sinker-controlling portion of the unit will select sinkers which are actually operative with respect to an adjacent yarn feed.

Conveniently, two ends of yarn will be fed simultaneously to the needles and the plush pile 50 will be produced by adjustment of the sinkers to a position which inserts a high part 143 of the sinker between the uppermost one of the two 55 yarn ends. This is shown clearly in Figure 10. Consequently, relatively longer sinker loops will 60 be drawn from the upper yarn and as the needles are actuated to draw the loops the extra lengths thus produced from the upper yarn will be left standing above the normal ground fabric surface knitted from the lower yarn. In Figures 10 and 65 11 upper and lower yarns are indicated by reference numerals 70 and 71 respectively. Figure 11 indicates the position of adjustment of a sinker 43 when a plush pile sinker loop is not required and in this case both yarns will be drawn over a 65 relatively low sinker surface 243. The lower surface will be always utilized by the lower yarn 71 and if a plush pile loop is to be formed the sinker will be adjusted, by the action of the pattern drum 20, from the position of Figure 11 to that 70 of Figure 10 and in this adjustment the high part of the sinker enters between the two yarns so that the lower or ground yarn will be drawn over the low portion 243 of the sinker, and the plush pile yarn over the high part 143.

Figure 6 shows the position of a sinker before it is adjusted by the pattern drum to produce a plush pile loop, or alternatively it may be understood as showing the position of any individual sinker when the pattern drum 20 fails to select it. Figure 5 illustrates in full and chain lines the passage of a sinker inwardly during the selective action of the pattern drum 20 and Figure 7 shows the fully selective position, the relative positions and movements of the intermediate slider 42 being clearly shown.

The selector cams controlled from the pattern drums may be so carried as to permit of angular adjustment about the axis of the machine. In the illustrated example the cams 26 associated with the pattern drum 20 are shown as carried in this way by means of a ring 72 from which the spindle 27 depends. The spindle travels in an arcuate slot 73 in the upper member 45 of the sinker ring and ring 72 may be arranged for angular adjustment.

This angular adjustment of the cams 26 permits of an accurate initial setting of these cams relatively to the cam followers such as 29, and moreover it permits of the movement of an automatic or other adjustment of the cams as a body into and out from operative positions relatively to the cam followers. For example, if ring 72 is adjusted to its fullest extent in an anti-clockwise direction, as shown in Figure 2, the noses of the cam followers 29 will come opposite to depressions 75 in the cams 26 and in this position movement of the cam followers 29 will fail to actuate the cams. On the other hand, in the position illustrated in Figure 2 the cams are shown as having been adjusted to a position at which the cam followers are fully operative on the cams. The cams 31 associated with the lower cylinder are not shown as being so adjustable although the lower bracket 56 may be circumferentially and radially adjustable on the plate 57 if desired.

It will be understood and appreciated that racking and bluffing control with means operated by the bluff for reversing rotation of either or both the pattern drums may be employed in a manner similar to that described and illustrated in the copending United States application, Serial No. 47,681.

It is to be understood that although the invention has been described in detail in connection with pattern drums or wheels it is within the scope of the invention to employ other patterning means such, for example, as jacquard means or any other form of pattern control that may be found desirable or preferable in any particular case.

We claim:

1. In a knitting machine, comprising a needle bed and needles therein, the combination of needle-selecting patterning means comprising a rotatable patterning member operative selectively upon the needles to produce patterns by stitch changes in selected areas of the ground fabric, knitting elements to produce a plush pile, a rotatable patterning member operative selectively upon said plush pile-producing elements for the purpose of producing a plush pile pattern in other selected areas of the ground fabric, and driving means common to both rotatable patterning members.

2. In a knitting machine, comprising a needle bed and needles therein, the combination of needle-selecting patterning means comprising a rotatable patterning member operative selectively upon the needles at one feed to produce patterns

by stitch changes in selected areas of the ground fabric, knitting elements to produce a plush pile, a rotatable patterning member operative selectively upon said plush pile-producing elements at another yarn feed for the purpose of producing a plush pile pattern in other selected areas of the ground fabric, and driving means common to both rotatable patterning members.

3. In a knitting machine, comprising a needle bed and needles therein, the combination of needle-selecting patterning means comprising a rotatable patterning member operative selectively upon the needles to produce patterns by stitch changes in selected areas of the ground fabric, knitting elements to produce a plush pile, a rotatable patterning member operative selectively upon said plush pile-producing elements for the purpose of producing a plush pile pattern in other selected areas of the ground fabric, and driving means common to both rotatable patterning members, the said drive for the rotatable patterning members comprising an operating spindle and pawl-and-ratchet mechanisms operated thereby for driving the individual rotatable patterning members.

4. In a knitting machine, comprising a needle bed and needles therein, the combination of needle-selecting patterning means comprising a rotatable patterning member operative selectively upon the needles at one feed to produce patterns by stitch changes in selected areas of the ground fabric, knitting elements to produce a plush pile, a rotatable patterning member operative selectively upon said plush pile-producing elements at another yarn feed for the purpose of producing a plush pile pattern in other selected areas of the ground fabric, and driving means common to both rotatable patterning members, the said drive for the rotatable patterning members comprising an operating spindle and pawl-and-ratchet mechanisms operated thereby for driving the individual rotatable patterning members.

5. In a knitting machine, comprising a needle bed and needles therein and a needle cam carrier between which and the bed there is relative movement for knitting purposes, the combination of needle-selecting patterning means comprising a rotatable patterning member operative selectively upon the needles to produce patterns by stitch changes in selected areas of the ground fabric, knitting elements to produce a plush pile, a rotatable patterning member operative selectively upon said plush pile-producing elements for the purpose of producing a plush pile pattern in other selected areas of the ground fabric, and driving means common to both rotatable members and comprising a spindle operatively connecting the said rotatable members, a double armed rocking lever on said spindle, a cam relatively movable past the rocking lever in synchronism with the moving part of the knitting machine in order to engage and move the two arms of the double armed lever in succession in order to rock the spindle, and pawl-and-ratchet mechanisms operated thereby to transmit the drive from the rocking spindle to the rotatable members.

6. In a knitting machine, comprising a needle bed and needles therein and a needle cam carrier between which and the bed there is relative movement for knitting purposes, the combination of needle-selecting patterning means comprising a rotatable patterning member operative selectively upon the needles at one feed to pro-

- duce patterns by stitch changes in selected areas of the ground fabric, knitting elements to produce a plush pile, a rotatable patterning member operative selectively upon said plush pile-producing elements at another yarn feed for the purpose of producing a plush pile pattern in other selected areas of the ground fabric, and driving means common to both rotatable members and comprising a spindle operatively connecting the said rotatable members, a double armed rocking lever on said spindle, a cam relatively movable past the rocking lever in synchronism with the moving part of the knitting machine in order to engage and move the two arms of the double 10 armed lever in succession in order to rock the spindle, and pawl-and-ratchet mechanisms operated thereby to transmit the drive from the rocking spindle to the rotatable members.
7. In a circular knitting machine, comprising 15 a needle bed and needles therein, the combination of needle-selecting patterning means comprising a rotatable patterning member operative selectively upon the needles to produce patterns by stitch changes in selected areas of the ground 20 fabric, knitting elements to produce a plush pile, a rotatable patterning member operative selectively upon said plush pile-producing elements for the purpose of producing a plush pile pattern in other selected areas of the ground fabric, and 25 driving means common to both rotatable patterning members, the said rotatable needle and plush pile-patterning members being arranged respectively at different levels.
8. In a circular knitting machine, comprising 30 a needle cylinder and needles therein, the combination of needle-selecting patterning means

comprising a rotatable patterning member operative selectively upon the needles at one feed to produce patterns by stitch changes in selected areas of the ground fabric, knitting elements to produce a plush pile, a rotatable patterning member operative selectively upon said plush pile-producing elements at another yarn feed for the purpose of producing a plush pile pattern in other selected areas of the ground fabric, and driving means common to both rotatable patterning members comprising a vertically disposed spindle interconnecting a rotatable plush pile-patterning member above a rotatable needle-selecting patterning member.

9. In a knitting machine, needle-selecting patterning means and sinker-selecting patterning means, both comprising intermittently rotatable patterning elements, and driving means common to both patterning elements, said driving means comprising an operating spindle and pawl-and-ratchet mechanisms operated thereby and operatively connected to the individual rotatable patterning elements.

10. In a knitting machine comprising a plurality of yarn feeds, the combination of a rotating patterning element for needle selection at one yarn feed, a rotating patterning element for sinker selection associated with an adjacent yarn feed, and driving means common to both said rotating patterning elements, said driving means comprising an operating spindle and pawl-and-ratchet mechanisms operated thereby and operatively connected to individual rotating patterning elements.

LESLIE HERBERT LEEDHAM. 35
